SNACK FOOD PRODUCT OR THE LIKE

William E. La Mothe and Gertrude Le Ann Borchers,
Battle Creek, Mich., assignors to Kellogg Company,
Battle Creek, Mich., a corporation of Delaware

Filed Jan. 29, 1969, Ser. No. 15,555

Term of patent 14 years

Int. Cl. D1—01

U.S. Cl. D1—13

FIG. 1 is a plan view of a snack food product or the like showing our new design;

FIG. 2 is an end elevation thereof;

FIG. 3 is a side elevation thereof; and

FIG. 4 is a section thereof taken substantially on line 4—4 of FIG. 1.

We claim:

The ornamental design for a snack food product or the like, substantially as shown.
